UNITED STATES PATENT OFFICE

JOSEPH J. PERLMAN AND NATHAN H. PERLMAN, OF CHICAGO, ILLINOIS, ASSIGNEES
TO HANDY BUTTON MACHINE CO., OF CHICAGO, ILLINOIS, A CORPORATION OF
ILLINOIS

TUFTING BUTTON

Application filed July 13, 1931. Serial No. 550,572.

This invention relates to a tufting button or buttons for use with mattresses, cushions, pads, hammocks, and the like, and also to a method of tufting.

One of the objects of the invention is to provide an inexpensive method of tufting mattresses, hammocks, cushions, pads and the like in an expeditious manner and in a way which will prevent the thread, tape, etc. from tearing through the cover and will also enhance the appearance of the tufted article. Another object is to provide a tufting button which may be used with a pre-formed tufting thread or tie element, the button being readily inserted below the outer loop portion of the tie element and being provided with means for retaining it securely in position. Another object is to provide a tufting button adapted to be used with a machine thread or so-called two-way thread, the relatively wide flanges of the button being slotted to receive the looped ends of the thread so as to support the thread near the points where it passes through the mattress cover or ticking. Another object is to provide a tufting button having relatively wide flanges which may be used with mattresses which are sewed by hand, the button being designed to retain the thread securely within the button and below the plane of the flange thereof. Other objects and advantages will appear as the specification proceeds.

The invention is fully described in the following specification and shown in the accompanying drawing, in which—

Figure 1 is a broken sectional view of a mattress showing the tufting button or buttons secured thereto, in accordance with my invention; Fig. 2, a bottom plan view of one form of button embodying my invention; Fig. 3, a top plan view; Fig. 4, a sectional view of the button in normal position, the section being taken as indicated at line 4 of

Fig. 2; Fig. 5, a sectional view of the button

as applied to a mattress, the section being taken as indicated at line 5 of Fig. 3; Fig. 6, a plan view of a modified form of button embodying my invention; Fig. 7, a sectional view of the modified form of button shown in Fig. 6, the section being taken as indicated at line 7 of Fig. 6; and Fig. 8, a sectional view of the modified form of button, the section being taken as indicated at line 8 of Fig. 6.

In the illustration given, A designates a mattress, B a thread or tie element, and C a tufting button.

The mattress A may be of any desired construction. If desired, the invention may be employed with cushions, pads and the like.

The tie element B may be formed of thread, twine, tape, wire, etc. It is preferred to use thread, twine, or tape. Also, it is preferred to sew the mattress by the two-way method, the thread passing through the mattress and being looped over a short distance, say one-quarter of an inch, and then passed back through the mattress parallel to the other thread. After having been passed through the mattress, the free ends of the loop thread are tied, forming knot B'.

The button C is preferably formed with a wide circular flange 1 having a downwardly curved peripheral edge 2. The central portion of the button is drawn downwardly to form a shallow depression or dished portion 3. The extreme central portion of the button is cupped upwardly to form a round seat 4 adapted to receive the thread or tie member B and to protect the thread from the rough edge of the metal. Diametric slots 5 are formed through the flange 1 and a portion of the depressed button portion 3. The slots are preferably wider on their inner sides and converge slightly toward the peripheral portion of the button, thus forming a narrow neck or thread retaining constriction 6.

As shown more clearly in Figs. 1 and 5,

the curved flange 2 provides between it and the depressed button portion 3 a housing or channel 7 which is adapted to receive the knot B' of the thread or tape B, and to conceal it substantially from view.

The form of button shown in Figs. 1 to 5, inclusive, is adapted to be used with a pre-formed thread, as well as with thread sewed by hand. The pre-formed thread may be formed so that the parallel thread portions forming the loop pass through the mattress substantially in contact with each other, or the looped thread may be formed by the two-way method illustrated in Fig. 1, the thread passing through the mattress, then being looped over a short distance, say one-quarter of an inch, and then passed back through the mattress so as to run parallel to the first thread. The latter method is what is generally employed in machine stitching or tufting. The present tufting button is admirably adapted for use with thread loops formed by the machine method. The wide flanges 1 of the button afford the relatively long slots 5 which receive the opposed loop portions and support them near their points of emergence from the mattress cover. The narrow neck 6 at the outer periphery of the button serves to retain the threads securely within the slots. The housing 7 provided by flange 2 and the depressed portion 3 is adapted to receive the knot B'.

The form of button described lies flat upon the top of the mattress and presents an even smooth top surface, the downwardly curved flange 2 making contact with the mattress cover or ticking. The tie member B is prevented from being drawn through the mattress ticking by the button C and also by the fabric A', which extends between the two portions of the thread forming the loop. A double security against tearing of the mattress cover is thus provided. The upwardly cupped portion 4 of the button provides a round seat adapted to receive the tie member B, and preventing it from being cut or worn by contact with the button.

In the modified form of button illustrated in Figs. 6, 7 and 8, 8 designates the outer relatively wide flange portion of the button, 9 the oblong openings in the button which are disposed on opposite sides of a median line, and 10 designates a saddle or thread seating portion between the openings 9. As illustrated more clearly in Figs. 7 and 8, the saddle portion 10 is extruded downwardly below the plane of flange 8. Preferably, the saddle is formed sufficiently low to support the thread below the plane of flange 8. The saddle 10 is longitudinally curved to form a rounded seat 11 upon which the tie member B may rest. The knot B' may be drawn below flange 8, the saddle portion 10 providing between it and flange 8 a relatively wide space in which the knot may be housed.

The form of button illustrated in Figs. 6, 7 and 8 is particularly adapted for hand stitching or sewing. The walls of openings 9 are continuous and prevent the thread from being accidentally removed therefrom. The saddle being drawn sharply downwardly, greatly increases the size of openings 9, thus permitting the thread to be easily passed therethrough and over the saddle 10. In the hand stitching operation, the tie member B is passed through the mattress and, by a movement substantially parallel with the top surface of the mattress, through the openings 9 of the button. The tie member is then passed back through the mattress and similarly through the openings 9 on the opposite side of the mattress. The member B may then be drawn tight and tied, with the knot B' disposed below flange 8, or if desired, drawn through the mattress cover into the body of the mattress. By referring to Fig. 7, it will be observed that the needle containing the tie element B may be readily passed through openings 9 by movement substantially parallel with the flange 8; i. e., it is not necessary to pass the needle up through flange 8 and then down through the other opening in flange 8, but the entire course of the needle may be below the flange.

The foregoing detailed description has been given for clearness of understanding only and no unnecessary limitations should be understood therefrom, but the appended claims should be construed as broadly as permissible in view of the prior art.

We claim:

1. A tufting button adapted for use with mattresses and the like equipped with tie loops, said button comprising a wide circular flange provided with a downwardly curved peripheral portion, an integrally depressed inner portion lying below said flange, and an upwardly cupped central portion the top of which is in substantial alignment with the peripheral edge of said flange, said button being provided with slots extending from the periphery of the flange to said cupped portion.

2. A tufting button, adapted to be slipped into engagement with the loops of mattresses and the like, comprising a wide flange adapted to rest directly upon the mattress ticking, said flange being provided with a downwardly curved periphery, a depressed inner portion integral with said flange and aligned below the plane of said flange, and an upwardly cupped central portion having its top in substantial alignment with the peripheral edge of said flange, said button being provided with diametrically opposed slots extending from the periphery thereof to said cupped portion.

3. A tufting button adapted for use with mattresses and the like equipped with loop tie elements, said button comprising a wide

circular flange having a downwardly curved peripheral edge, a depressed inner portion slightly below the plane of said flange and having an upwardly cupped portion the top of which is in substantial alignment with the edge of said flange, said button being provided with diametrically opposed slots constricted at their peripheral edge but widened near the central portion of said button.
